CIGARETTE HOLDER

Jack Datsko, Los Angeles, Calif.

Application December 16, 1941, Serial No. 423,143

5 Claims. (CL. 131—182)

This invention relates to smokers' articles generally known as cigar or cigarette holders and has for an object the provision of a holder which is compact, inexpensive, and pleasing in appearance, and which does not differ materially in size and general outline from holders now in common use.

Another object is to provide a holder of the class described having an inner tube for holding the butt end of the cigar or cigarette which can be removed from an outer casing and opened so that the tube can be cleaned throughout its entire length. The cleaning of the outer shell is also greatly facilitated.

Another object is to provide a holder of the class described with a simple form of ejector which may, if desired, be equipped with a renewable filter.

Additional advantages and objects of the invention will appear from the following detailed description of a preferred embodiment of the invention. It will be understood, however, that various modifications may be made in the details of construction without departing from the essentials of the invention as defined by the appended claims.

Referring now to the drawing:

Figure 1 is a view of a holder embodying the invention;

Figure 2 is a longitudinal sectional view of the holder, Figure 1;

Figure 3 is an enlarged view of the holder shown in the preceding figures showing the ejector mechanism;

Figure 4 is a view of the holder shown in the preceding figures; and

Figure 5 is a fragmentary plan view of Figure 4.

It will be understood that the present invention may be applied to holders for either cigarettes or cigars, the only difference being in the diameter of the bore to receive the butt. Therefore, when cigarettes are referred to hereinafter, it will be understood that this includes cigars.

The numeral 10 denotes an outer tubular shell which may be made of any suitable material, preferably a plastic molding of Bakelite or the like. This has a bore sufficiently large to take the inner tube, to be presently referred to. This bore is enlarged at one end to form a chamber to receive the enlarged end of the inner tube. The inner tube, generally denoted by the numeral 11 is made of two complementary sections as shown in Figure 4 at 11a and 11b. These are hinged in any suitable manner as shown at 12. When folded together, the seam, or joint, will be reason-

ably tight because the inner tube fits close within the bore of the outer shell 10, so that the parts of the inner tube are held in smoke-tight relation with each other.

If any smoke should leak out between the halves of the inner tube, the smoker will draw it in his mouth as the outer shell 10 completely surrounds the inner tube at all points where smoke could escape therefrom. The inner tube 11 near its outer end is enlarged as shown at 13 to receive the butt of the cigarette. At the extreme outer end of the enlarged form, slots 14, 15 are provided, and the adjacent walls of the tube are partly flared outwardly in order that when the tube is forced into the outer shell 10 it will fit closely therein.

The shell 10 has a longitudinal open-ended slot 16 which may, if desired, be stepped as shown in Figure 4. The tube 11 lying immediately below this slot has another slot 17 which is closed at both ends as shown at Figure 3. Through these slots extends the shank 18 of the ejector button 19, to which shank is also secured a slide 20 longitudinally movable with the ejector.

The inner end of the shank 18 is riveted to a filter holder 21 which may comprise a U-shaped piece, as more clearly shown in Figure 5, adapted to support a disc of suitable filter material 21a. The filter holder 21 lies transversely of the bore of the tube 11, and therefore presents a face 22 to the butt of the cigarette, so that when the ejector button is moved to the right, Figure 2, it will engage the butt of the cigarette and push it out of the inner tube. Continued movement of the ejector button to the right will ultimately bring shank 18 of same against the wall of the outer end 23 of the slot 17 of the inner tube. If continued outward pressure is applied to the ejector button while the outer shell 10 is held, the inner tube 11 will be forced out of the outer shell 10.

The inner tube may be opened and cleaned from end to end, and the outer shell 10 can be easily cleaned because the bore thereof is quite large as compared to the bore in ordinary cigarette holders. Obviously, the larger the bore, the easier to clean.

It will be observed by reference to Figure 2 that a chamber 24 exists behind the ejector button, and in this chamber can be placed any kind of a suitable filter cartridge, and the small filter heretofore mentioned, if carried is the filter 21, can be omitted.

As the hinge 12 lies within a longitudinal recess formed in the inner wall of the outer shell 10, the

inner tube 11 is prevented from turning therein, and this arrangement tends to prevent any binding that might otherwise take place in connection with the accurate location of the shank 18 of the ejector means in its associated slide 20.

What is claimed is:

1. A holder of the class described comprising an outer tubular shell having an interior hinge-receiving recess in the bore thereof and an interior slot in its side wall parallel to said recess and spaced apart therefrom, a removable two-piece inner tube adapted to fit within said shell, said pieces being hinged together and said hinge fitting within said hinge-receiving recess in the shell, said tube having a slot therein adapted when said tube is in place in said shell to overlie the slot in the latter, and ejector means extending from outside said shell through said slots and into the bore of the tube, said means being longitudinally slidable along said shell and including a U-shaped filter holder in said bore. 20

2. A holder of the class described comprising a pair of complementary members hinged longitudinally and adapted when folded together to form a tube having a bore extending therethrough and having an enlarged portion at one end adapted to receive a cigar or cigarette, said members also forming a chamber positioned rearwardly of said enlarged portion, a U-shaped clip in said chamber filter means in said clip mounted within the fingers of some so as to be readily removable therefrom, and means for securing said members together in operative relationship for use in smoking. 25

3. In a holder of the class described, an outer tubular shell having an open-ended slot extending longitudinally of said shell from one end thereof, an inner tube in said shell having a slot with closed ends and extending longitudinally of said tube and lying immediately below said slot in the shell, and a movable member having 35

5 a head lying above the outer surface of said shell and a shank extending through both said slots and to the bore of said tube, said member adapted when pushed outwardly in said slots toward the adjacent open end of the holder to first eject the butt of a cigarette therefrom, said member upon further travel toward the adjacent end of the holder, engaging the transverse wall of said tube to force same out of said shell whereby said tube and shell can be completely separated while said member remains attached to said tube. 10

4. A holder of the class described comprising an outer tube adapted to act as a smoke conduit and forming an integral mouthpiece at its inner end, and having an open slot extending inwardly from its outer end, a longitudinally hinged inner tube adapted to fit within said outer shell and to grasp and hold a cigarette in its outer end, said inner tube normally overlying the entire inner surface of said outer tube from end to end thereof, and means connected to said inner tube and extending through said slot in said outer tube whereby said inner tube can be pushed completely out of said outer tube. 15

5. A holder of the class described comprising an outer tubular shell having an enlarged bore at its outer end and forming an integral mouthpiece at its inner end, a longitudinally hinged inner tube adapted to fit within said outer shell and to grasp and hold a cigarette in its outer end, said inner tube normally overlying the entire inner surface of said outer shell from end to end thereof, said inner tube having a chamber therein intermediate its ends, ejector means extending into said chamber and through the side walls of said shell and tube and longitudinally slid able therealong, and including a U-shaped member in said chamber and a removable filter carried by said member. 30 40
